UNITED STATES PATENT OFFICE.

THOMAS J. PORRO, OF TACOMA, WASHINGTON.

RAPID-MIXING FLASK.

Application filed March 15, 1926. Serial No. 94,764.

This invention relates to flasks for mixing liquids.

The objects of the invention are, first, to provide separate containers, each of which is adapted to receive and hold a distinct liquid therein, each of said containers being adapted to stand alone on its own base; second, to shape the necks of said containers whereby the orifice of one may be inserted 10 into the orifice of the other; third, to shape the bulbs of the containers whereby, when the vessels are tipped with their necks in alignment in a horizontal line and one is inserted in the other, the liquids may still be held 15 in their respective bulbs and out of contact with each other and, whereby, when the bulbs are turned to extend upward into mixing position, the necks of the two containers form a continuous straight and smooth passage between the lowest points of each of the 20 two bulbs, thereby permitting the rapid and complete mixing of the liquids by surging the combined liquids from end to end of the passage.

I attain these and other objects by the devices, forms and shapes illustrated in the accompanying drawings, in which—

Figs. 1 and 2 are side elevations of the two flasks, in position for receiving the 30 respective liquids; Fig. 3 is an elevation of the vessel formed by the two flasks when tipped and connected together, the liquids therein being still held in the respective flasks; and Fig. 4 is a vertical section of the 35 flasks forming the mixing vessel when turned into mixing position.

Similar numerals of reference refer to similar parts throughout the several views.

In many of the arts and professions it is 40 necessary to mix liquids suddenly and rapidly in order to attain the desired quality or kind of mixture between the several liquids, for instance, in biological laboratories this is necessary in order to obtain an unstable colloidal mixture such as is necessary to perform the required tests.

Referring to the drawings it will be seen 50 that I provide two similar flasks 1 and 2, each of which is provided with a bulb or containing chamber 3, having a flat bottom 4, on which it may be independently stood, and a neck 5 which is offset from the usual position and is arranged so that its lowest line, when the flask is turned down as in Fig. 4, is in alignment with the lowest line of the bulb or body of the flask. The orifice 6 of the neck

5 of the flask 1 is slightly enlarged and its inner surface is ground to an accurate conical shape. The outer surface of the end 7 of the neck 5 of the flask 2 is reduced and 60 ground to fit tightly in the above mentioned orifice 6. The two necks 5 therefore form a continuous passage which, if the flasks are placed with their bulbs 3 upward (Fig. 4), forms a smooth continuous chamber into 65 which the liquids in the said bulbs 3 have been emptied and in which they may be violently or rapidly shaken or surged to thoroughly and completely mix them and to produce the desired quality of mixture or suspension of the substances in the combined 70 liquid.

My improved flasks are used in the following manner:—Flasks 1 and 2 are first 75 stood on their flat bottoms 4 (Figs. 1 and 2) and the measured quantities of the several liquids are placed therein, one liquid in each; they are then turned with their necks away from each other, as in Figs. 1 and 2; they are then held in the two hands of the 80 operator and are tipped in opposite directions to bring their necks 5 in line with each other, the bulbs 3 being lower than the said necks 5 will still contain the liquids which were placed therein; then the end 7 of the 85 flask 2 is inserted into the orifice 6 of the flask 1; and then the combined vessel, thus formed, is turned on the longitudinal axis of the necks 5 to bring the bulbs 3 above the level of the said necks and to cause the two 90 liquids to fall therefrom into the passage or vessel formed by the necks, and the sides of the bulbs 3, and then, at once, the combined vessel is agitated horizontally to cause the liquids therein to surge from end to end of 95 the passage and to thus become rapidly mixed.

Thus it will be seen that I have provided a pair of flasks in which the bulbs are each offset from the neck and extend to one side 100 thereof so that, when the bulb portion of the flask is turned upward and the neck thereof is held horizontally, no portion of the bulb will lie below the line of the lower portion of the neck.

Having therefore described my invention, what I claim is:—

1. A device of the character described comprising a pair of similar complementary flasks, each adapted to receive a different liquid, each flask comprising a bulb portion and a neck portion, the neck of one flask be-

ing adapted to enter and fit in the neck of the other flask, whereby the two necks form a single continuous mixing passage, each bulb being offset from the neck and extending to one side thereof whereby, when the necks are in closed connection with each other and the bulbs are turned downward, the several liquids are held therein and whereby, when the vessel thus formed is ro-

tated to bring the two bulbs upward, the liquids are emptied into the mixing passage formed by the necks and may be agitated and mixed therein. 10

2. A device as set forth in claim 1, wherein each bulb has a flat bottom whereon it 15 may stand when the neck thereof is in vertical position.
